UNITED STATES PATENT OFFICE.

CHIHIRO NAKAIZUMI, OF TOKYO, JAPAN.

ROLLING STAMP.

1,374,090.

Specification of Letters Patent.

Patented Apr. 5, 1921.

Application filed September 4, 1919. Serial No. 321,733.

To all whom it may concern:

Be it known that I, CHIHIRO NAKAIZUMI, of Tokyo, Japan, a subject of His Majesty the Mikado of Japan, have invented new and useful Improvements in Rolling Stamps, of which the following is a specification.

This invention relates to improvements in revolving hand-stamps of the type in which a double faced stamp-body is used and an inking pad is incorporated in the handle. The object of the invention is to provide such stamp which is durable and simple in construction and perfect in operation. According to my invention, an improved means is provided for turning the stamp-body and for holding it normally in the vertical position.

Annexed drawings illustrate my invention, in which:—

Figure 1 is a longitudinal section of the stamp according to my invention.

Fig. 2 is an end view thereof.

Figs. 3 and 4 are front views of the essential parts of the invention, Fig. 4 showing the stamp-body assuming the position in which it is pressed on the article to be stamped, and dotted lines in Fig. 3 showing such stamp-body in partially revolved position.

Similar reference numerals refer to similar parts throughout the drawings.

Referring to the drawings, 1 is a handle of any convenient form and of the desired length and is provided at its lower end with an ordinary inking pad 2. On one side of the handle 1 is a box 3 containing a spiral spring 5. Located diametrically opposite to the said box 3 and pivoted to the handle 1 in any suitable manner is a supporting spring 4, of which the extremity is hooked as at a. 6 is a stamp supporting rod, one end of which is bent at right angles to form a shaft b for the stamp body. At the other end said rod 6 is formed with a head or sliding member c which is located within the box 3 and bears against the lower end of the spiral spring 5.

The stamp body 7 is provided with a radial hole for receiving the shaft b, i. e., the bent portion of the rod 6. The body 7 is double-faced and on each face thereof, dies 9 for indicating the year, month and day or other desired marks, are clamped by means of a ring 8 screwed to the body. Secured to or made integral with the stamp body is an elongated hexagonal block or ear e

formed with a concavity, in which an oblique ridge or high portion i is formed, such high portion being lower than the edge of the concavity, as shown in Fig. 1. From the drawing it will be seen that the hook a of the spring 4 normally bears against the inner edge of the concavity of the ear at one of the oppositely located acute angled portions, thus holding the stamp body in vertical position. It will also be seen that by disengaging the hook a of the spring 4 from the ear e and turning it about its pivot, the stamp body 7 can be easily detached from the shaft b.

In operation, the handle 1 being held in the hand is violently pressed against the paper or plate to be stamped, the spiral spring 5 in the box 3 being compressed by the rod 6, and the hook a of the spring 4 passing the high portion i in the concavity of the ear e and assuming the position shown in Fig. 4. At this time the upper face of the stamp body is pressed against the inking pad in the usual manner. As soon as handle 1 is raised, the said hook a will slide along the lower inclined edge of the ridge i and will come to the right hand corner (in Fig. 4) or angle of the lower triangle and, as the point of support is thus transversely shifted from the axis of rotation of the stamp body as shown in dotted lines in Fig. 3, the stamp body will be turned by the action of the spring 5. Then it is prevented from overturning and is held in vertical position by the hook a of the spring 4, as shown in full lines in Fig. 3. In the manner described, the stamping operation can be continuously effected.

What I claim is:—

1. In a stamp of the type referred to, the combination with a stamp body rotatably supported, of a supporting rod bent at one end at right angles to form a shaft for the stamp-body and at the other end bearing against a spiral spring contained in a box attached to the handle, an ear secured to or made integral with the stamp body and provided with a concavity in which a ridge or high portion is obliquely arranged, and a supporting spring formed at its extremity with a hooked portion normally engaging the uppermost inner edge of the said concavity.

2. In a stamp of the type referred to, the combination with a stamp body rotatably supported, of a supporting rod bent at one

- end at right angles to form a shaft for the stamp body and at the other end bearing against a spiral spring contained in a box attached to the handle, an ear secured to or made integral with the stamp body and provided with a concavity in which a ridge or high portion is obliquely arranged, and a supporting spring formed at its extremity with a hooked portion normally engaging the uppermost inner edge of the said concavity, the arrangement being such that when the handle is pressed against the article to be stamped, the hook of the supporting spring will pass the ridge in the concavity.
- 15 3. In a stamp of the type referred to, the combination with a stamp body rotatably supported, of a supporting rod bent at one end at right angles to form a shaft for the stamp body and at the other end bearing

against a spiral spring contained in a box 20 attached to the handle, an ear secured to or made integral with the stamp body and provided with a concavity in which a ridge or high portion is obliquely arranged, and a supporting spring formed at its extremity 25 with a hooked portion normally engaging the uppermost inner edge of the said concavity, the arrangement being such that, as soon as the pressure of the compressed spiral spring prevails, the hook located in the 30 underside of the ridge is guided along the inclined edge thereof, whereby the point of support is shifted transversely from the axis of rotation of the stamp body and the latter thus turned half a revolution about its axis 35 by the action of said spiral spring.

CHIHIRO NAKAIZUMI.
